(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design;

FIG. 2 is another embodiment thereof;

FIG. 3 is another embodiment thereof;

FIG. 4 is another embodiment thereof;

FIG. 5 is another embodiment thereof;

FIG. 6 is another embodiment thereof;

FIG. 7 is another embodiment thereof;

FIG. 8 is another embodiment thereof;

FIG. 9 is another embodiment thereof;

FIG. 10 is another embodiment thereof;

FIG. 11 is another embodiment thereof; and,

FIG. 12 is another embodiment thereof.

The outermost broken lines illustrate a display screen or portion thereof. The remaining broken lines illustrate portions of the graphical user interface. None of the broken lines form part of the claimed design.
